UNITED STATES PATENT OFFICE.

ADALINE A. ROCKWELL, OF NEW YORK, N. Y.

DESIGN FOR RUCHES.

Specification forming part of Design No. 7,406, dated April 28, 1874; application filed April 6, 1874.
[Term of Patent 3½ years.]

To all whom it may concern:

Be it known that I, ADALINE A. ROCKWELL, of the city, county, and State of New York, have invented a Design for Ruches, of which the following is a specification:

The nature of my design is fully represented in the accompanying drawing, to which reference is made.

Figure 1 is a view, in perspective, of a ruche made in accordance with my design; and Fig. 2, a transverse profile of the same.

A represents the exterior and B the interior portions or borders of the ruche, both formed of ruffles or flutings, the transverse sections of which are of mainly circular or loop-like profile, as shown in Fig. 2, with rolling or rounded outer edges, terminating at their backs and inner edges in flattened or straight continuations, said round-edged and loop-like flutings,

the interior ones of which are larger or more prominent than the exterior ones, lying back to back. Within these two ruffles or flutings, A B, are a number of separate contiguous or closely-arranged duplex loops, C, having rolling or rounded edges C C, and the facial presentation of which is in line with the length of the ruche, and which are contracted or flattened at their inner edges or surfaces, where said loops join or lie between the inner edges or surfaces of the ruffles or flutings A B.

What I claim as my invention is—
The design for ruches, substantially as described, and shown in the annexed drawing.

ADALINE A. ROCKWELL.
